PULVERIZING JAW CRUSHER

Charles J. Zillgitt, Pasadena, Calif.

Application December 11, 1933, Serial No. 701,828

16 Claims.

(Cl. 83—53)

My invention relates to a pulverizing jaw crusher that is especially designed for crushing and pulverizing ore bearing rock and gravel and the principal objects of my invention are, to provide a relatively simple, practical and inexpensive apparatus that may be economically employed for the comparatively rapid crushing and pulverizing of various material and to provide an apparatus wherein the pulverizing action is accomplished by the combined reciprocating movement and jaw action of a shoe or plate that is positioned for operation immediately adjacent to a fixed plate or jaw.

A further object of my invention is, to provide in a machine of the character referred to, a movable jaw or plate which during a part of its operation, moves toward the fixed jaw or plate so as to function as a fulcrumed jaw in crushing material that is interposed between the two jaws or plates.

Further objects of my invention are, to provide simple and effective means for controlling the movements of the reciprocating plate with respect to the fixed plate, to provide a pulverizer wherein the pulverized material, when reduced to the proper degree of pulverization, is caused to pass through screens with water that is splashed upwardly from the pulverizing plates as a result of the movement of the reciprocating plate and further, to provide simple and efficient means for regulating the feed of material into the chamber or pocket where the pulverizing action is accomplished.

With the foregoing and other objects in view my invention consists in certain novel features of construction and arrangements of parts that will be hereinafter more fully described and claimed and illustrated in the accompanying drawings in which:

Fig. 1 is a top plan view of my improved pulverizing machine.

Fig. 2 is a vertical longitudinal section taken on the line 2—2 of Fig. 1.

Fig. 3 is an enlarged cross section taken on the line 3—3 of Fig. 2.

Fig. 4 is a top plan view of the reciprocating plate or shoe.

Fig. 5 is an enlarged detail section taken on the line 5—5 of Fig. 2.

Referring by numerals to the accompanying drawings that illustrate a preferred embodiment of my invention, 10 designates the main body of the pulverizer which is channel-shaped in cross section with upstanding flanges and the body member is mounted on suitable supports 11, so

that it occupies an angle of approximately ten or fifteen degrees with respect to a horizontal plane. The rear portion 12 of this body member is bent upward so that it occupies an angle of approximately fifteen or twenty degrees.

Arranged on the elevated end of member 10 are bearings 13 for a shaft 14 and that portion of the shaft between the bearings is provided with a crank 15.

Fly wheels 16 are mounted on the shaft outside the bearings 13 and one end of the shaft is extended in order to receive gearing or a belt wheel that is used in driving the pulverizer.

Secured in any suitable manner, preferably by means of bolts to the upper face of the lower portion of the channel-shaped body member 10, between the flanges thereof, is a fixed pulverizing plate 17 of hard wear resisting material and the upper face of this plate may be either plain or corrugated.

Journalized on the crank 15, is one end of an arm or beam 18 and suitably secured on top of the forward end of this beam, is a shoe 19, the upper face of which is formed on an irregular curve with the forward portion slightly higher than its rear portion. The length of this shoe is slightly greater than the throw of crank 15.

Arranged on the underside of the forward portion of beam 18 and rigidly secured thereto, preferably by means of bolts 20, is a plate 21 and formed integral with this plate on the upper side thereof, is a pair of spaced ribs or lugs 22.

These lugs or plates are spaced apart in order to form a channel 23 through which water may freely circulate while the pulverizer is in operation.

Detachably secured to the underside of plate 21, is a pulverizing plate 24 of hard wear resisting material that occupies a position immediately above the fixed pulverizing plate 17.

The rear portion of the reciprocating pulverizing plate 24, is curved upwardly to a slight degree as designated by 25.

Secured to and projecting upwardly from portions 10 and 12 of the channel forming the main body of the pulverizer are spaced transverse walls 25 and 26 and arranged between the side edges of these walls and the upper edges of those portions of the flanges on the body 10 between said walls, are sections 27 of reticulated material, preferably woven wire screens of small mesh.

Arranged immediately to the rear of wall 26, is a hopper 28 into which the material to be pulverized is fed, said hopper having an inclined

bottom and extending from the lower portion thereof inwardly and downwardly between the screens 27, is a short chute 29, having a feed opening 30 that is formed directly above the inclined bottom of hopper 28.

The flow of material through opening 30 is controlled by a vertically adjustable plate 31 that is arranged for sliding movement on the forward end of the chute and connected to the upper end of this sliding plate is the lower end of a threaded rod 32 that projects upwardly through a plate 33 and the latter being secured to the upper edges of walls 25 and 26.

A nut 34 is screw-seated on the threaded portion of rod 32 and provides means for raising and lowering said rod and the material feed control plate 31.

Arranged on the inclined bottom of the hopper to the sides of the opening 30, are vertically disposed plates 35 that confine the material that discharges through the opening 30 and hinged to the bottom of the hopper between the lower portions of these plates, is a short plate 36 that extends over the lower end of the fixed pulverizing plate 17.

Arranged beneath this hinged plate 36, is an expansive coil spring 37 that yieldingly resists downward swinging movement of said plate.

Secured to the forward end of arm or beam 18, 30 is a forwardly projecting finger 38, which when the beam approaches and moves rearwardly from its forward limit of travel, engages on top of the free end of plate 36 and swings the same downward against the resistance offered by spring 37, thereby vibrating said plate 36 and causing a portion of the material that has accumulated thereon to drop onto the forward portion of the fixed pulverizing plate 17.

Formed through one or both of the upstanding flanges or body member 10, immediately above the forward end of plate 17, are cleanout openings 39 that are normally closed by screw plugs 40 and which plugs may be readily removed from time to time to clean out any slime or residue that remains in the pulverizing chamber.

Arranged beneath the lower end of body member 10 and the lower portion of the up-turned end 12 thereof, is a transversely disposed launder 41, into which the pulverized material passes after being carried through the screens 27 at the sides of the pulverizing chamber.

Secured by bolts 42 to the upstanding flanges of body member 10, immediately adjacent to wall 25, is an inverted U-shaped frame 43 and projecting inwardly from the upper edges of the adjacent portions of the flanges of body member 10, are horizontally disposed plates 44 that are arranged to prevent water from splashing outwardly from the pulverizing chamber.

Secured to the central portion of the horizontal member of this frame 43, is a bracket 45, through which passes the threaded upper portion of a rod 46, the same extending downwardly into a tube 47 and the lower end of this tube is pivoted to beam 18, to the rear of shoe 19.

Interposed between a head on the lower end of rod 46 and the upper end of the tube, is an expansive spring 48 of such strength as to counter-balance and yieldingly support the weight of beam 18 and parts carried thereby.

A nut 49 is mounted on the threaded portion of rod 46 above the bracket 45 and provides means for adjusting the tension of spring 48.

Brackets 50 are mounted on the side portions of body 10, adjacent to the bearings 13 and piv-

otally mounted on said brackets are forwardly extending parallel arms 51 and journaled on a horizontal axis between the forward ends of these arms is a roller 52 that rides on the concave upper face of shoe 19.

The lower portions of threaded rods 53 are mounted for limited sliding movement through the forward ends of arms 51 and the upper portions of said rods are threaded through the top member of frame 43.

Mounted on the upper portions of these threaded rods and bearing on top of bracket 43, are lock nuts 54, whereby said rods may be raised or lowered.

The lower portions of the threaded rods 53 that pass through the forward ends of arms 51, are reduced in diameter, as designated by 55, and formed at the upper ends of said reduced portions are shoulders 56, which limits the upward movement of the forward ends of said arms 51 relative to said threaded rods.

Mounted on the intermediate portions of the threaded rods 53, are nuts 57, and arranged on said rods and interposed between said nuts 57 and the forward ends of arms 51, are relatively heavy expansive springs 58.

By screwing the nuts 57 upwardly or downwardly on the threaded rods, the tension of springs 58 may be varied and the positions of said threaded rods relative to the fixed frame 43 may be varied by screwing said rods upwardly or downwardly through the upper portion of said frame.

After the rods 53 have been raised or lowered they are retained in such positions by screwing the lock nuts 54 against the upper portion of frame 43.

Arranged on top of body member 10, a short distance in front of the bearings 13, is a transversely disposed partition 59 and formed through the bottom of body member 10, immediately in front of this partition, are apertures 60. Thus any oil that may drip from the crank shaft bearing and passing downwardly through the upper portion of body member 10, will drain through the openings 60 and thereby be prevented from traveling downward over the pulverizing plates and into the pulverized material that occupies the lower portion of the pulverizing chamber.

Arranged a short distance to the rear of partition 59 is a transverse partition 61, that is spaced apart from the upper surface of body member 10 and while the pulverizer is in operation, water is discharged onto the body member between the partitions 59 and 61 and this water passes through the space beneath partition 61 and flows downwardly over the pulverizing plates 17 and 24.

During the operation of my improved pulverizer material to be pulverized is delivered into hopper 28 and passes downwardly therethrough by gravity and such material passes through chute 29, through opening 30 and thence between walls 35 onto the vibrating plate 36.

On each forward stroke of beam 18, finger 38 strikes against the free end of plate 36, thereby depressing the same slightly and discharging a portion of the material from said plate onto the forward portion of the fixed pulverizing plate 17.

As shaft 14 is rotated, crank 15 imparts reciprocating movement to beam 18 and after the same reciprocates, the shoe 19 rides beneath roller 52 that is normally forced downward to its limit of movement by the heavy springs 58.

The irregular curved upper surface of shoe 19 is substantially higher at the forward end of said shoe than at the rear end and as a result of this

arrangement beam 18 occupies an inclined position when crank 14 is at the lowest point of its throw and with the beam so positioned crushing jaw 24 occupies an inclined position with respect to the upper surface of plate 17 and during the movement of crank 14 from its lowermost point upward to a substantially horizontal position, jaw 24 will be tilted downward onto the face of plate 17, thereby performing the functions of a jaw crusher and at the same time said jaw 24 will be moving forwardly over plate 17, thus crushing and reducing the interposed material by a direct jaw action, together with a reciprocating movement.

15 Thus the plate or jaw 24 will, during a portion of its movement, be moved directly toward the fixed jaw or plate 17, during which movement the beam carrying the movable body fulcrums on the roller 52 so that the apparatus performs the functions of a jaw crusher as well as a reciprocating jaw to effect the crushing and pulverizing of the material between the jaws.

During the first portion of the rearward stroke of beam 18 and as a result of the engagement 25 of the lower portion of the irregular curved upper face of shoe 19 with roller 52, crushing jaw 24 will be slightly elevated with respect to plate 19 so as to move rearwardly over said plate and during the latter portion of said rearward stroke, 30 jaw 24 will move downward toward plate 17 as a result of the engagement of the relatively high forward portion of shoe 19 with roller 52.

During the operation of the pulverizer, water is continuously delivered into the pulverizing 35 chamber, such water flowing beneath partition 61, thence downward over both pulverizing plates and the material that is pulverized to such a degree of fineness as to pass through the screens 27, will be carried upward and through said 40 screens with the water that is continually agitated and splashed by the movements of the reciprocating pulverizing plate 24.

All material discharging through the screens 27 will pass into and through the launder 41.

45 During operation, the spring 48 yieldingly supports the weight of reciprocating beam 18 and parts carried thereby and the upward movement of said beam is yieldingly resisted by springs 58.

The shoulders 56 on the threaded rods 53 limit 50 the upward movement of the roller carrying arms 52 and in the event that an uncrushable object such as a tool accidentally enters the pulverizer so as to exert abnormal pressure on the operating parts, the bolts 42 that connect frame 43 to the body member 10, will be sheared so as to 55 permit the frame to move upward without injury or breakage of any part of the machine other than the sheared, which may be readily replaced.

To achieve best results in pulverizing ore bearing rock and gravel, the pulverizer should be operated so that the beam 18 makes upwards of three hundred strokes per minute.

The springs 58 yieldingly resist the upward movement of the roller carrying arms 51 and 60 such resistance is sufficient to effect the pulverizing of the material between the jaws and when the roller carrying arms engage against the shoulders 56, further upward movement of said arms and the movable jaw is stopped and when 65 such action occurs and the movable jaw is tilted downward by the upward throw of the crank 14, the roller 52 functions as a fulcrum for the movable jaw to cause the same to operate as a positive jaw crusher.

70 In some instances it may be found desirable to

operate the machine as a dry crusher and pulverizer and when this is done the screens 27 are removed or covered with imperforate plates and one or more apertures are formed through member 10 immediately to the rear of the fixed jaw or plate 17.

Thus the material that is crushed and pulverized will be gradually drawn to the rear of plate 17 and said material will discharge through the openings to the rear of jaw 17 into a suitable 15 receptacle.

By varying the inclination of member 10 while the machine is being operated as a dry crusher and pulverizer, the degree of fineness to which the material is crushed and the speed of the 15 crushing and pulverizing operations may be readily controlled.

Thus it will be seen that I have provided a pulverizing jaw crusher that is relatively simple in construction, inexpensive of manufacture and 20 very effective in performing the functions for which it is intended.

It will be understood that minor changes in the size, form and construction of the various parts of my improved pulverizing jaw crusher may 25 be made and substituted for those herein shown and described without departing from the spirit of my invention, the scope of which is set forth in the appended claims.

I claim as my invention:

1. In a pulverizing jaw crusher, a body member, a pulverizing plate fixed to said body member, a beam mounted for reciprocatory movement above said body member, a pulverizing plate carried by said beam and arranged above said 35 fixed plate, a shoe on the beam above the pulverizing plate carried thereby the upper surface of which shoe is concave longitudinally and a spring held roller bearing on concave upper surface of said shoe.

2. In a pulverizing jaw crusher, a body member, a pulverizing plate fixed to said body member, a beam mounted for reciprocatory movement above said body member, a pulverizing plate carried by said beam and arranged above said fixed 45 plate, a shoe on the beam above the pulverizing plate carried thereby the upper surface of which shoe is concave longitudinally, a spring held roller bearing on the concave upper surface of said shoe, means for feeding said material to be pulverized 50 onto said fixed plate and screens arranged to the sides of said fixed plate.

3. In a pulverizing jaw crusher, a body member, a pulverizing plate fixed to said body member, a beam mounted for reciprocatory movement 55 above said body member, a pulverizing plate carried by said beam and arranged above said fixed plate, a shoe on the beam above the pulverizing plate carried thereby, the upper surface of which shoe is concave lengthwise, a roller bearing on 60 the concave upper face of said shoe, means for yieldingly resisting the upward movement of said roller and adjustable means for limiting the upward movement of said roller.

4. In a pulverizing jaw crusher, a body member, a pulverizing plate fixed to said body member, a beam mounted for reciprocatory movement above said body member, a pulverizing plate carried by said beam and arranged above 70 said fixed plate, a shoe on the beam above the pulverizing plate carried thereby, the upper surface of which shoe is concave lengthwise, a roller bearing on the concave upper face of said shoe, means for yieldingly resisting the upward movement of said roller, adjustable means for limiting 75

- the upward movement of said roller, means for delivering material to be pulverized onto said fixed plate and screens arranged to the sides of said fixed plate.
5. In a pulverizing jaw crusher, a body member, a pulverizing plate fixed to said body member, a crank shaft journaled on said body member, a beam journaled on the crank of said shaft, a pulverizing plate carried by the free end of said beam and disposed above the fixed pulverizing plate, adjustable means for counterbalancing the weight of the free end of said beam and the pulverizing plate carried thereby, a shoe on top of the free end of said beam the upper face of which shoe is concave longitudinally and a spring held roller for engaging the concave upper surface of said shoe and resisting the upward movement of the free end of said beam.
6. In a pulverizing jaw crusher, a body member, a pulverizing plate fixed to said body member, a crank shaft journaled on said body member, a beam journaled on the crank of said shaft, a pulverizing plate carried by the free end of said beam and disposed above the fixed pulverizing plate, adjustable means for counterbalancing the weight of the free end of said beam and the pulverizing plate carried thereby, a shoe on top of the free end of said beam the upper face of which shoe is concave longitudinally, a spring held roller for engaging the concave upper face of said shoe and resisting the upward movement of the free end of said beam, means for delivering material to be pulverized onto the fixed pulverizing plate and screens arranged to the sides of said pulverizing plate.
7. In a pulverizing jaw crusher, a fixed pulverizing plate, a pulverizing plate arranged for reciprocatory movement above said fixed plate, a shoe arranged above said reciprocating plate, the upper surface of which shoe is concave longitudinally and spring held means bearing on the concave upper surface of said shoe for yieldingly resisting the upward movements of said shoe and reciprocating plate.
8. In a pulverizing jaw crusher, a fixed pulverizing plate, a pulverizing plate arranged for reciprocatory movement above said fixed plate, a shoe arranged above said reciprocating plate, the upper surface of which shoe is concave longitudinally, spring held means bearing on the concave upper surface of said shoe for yieldingly resisting the upward movements of said shoe and reciprocating plate and means for supporting said reciprocating plate and shoe and maintaining the latter in engagement with said roller.
9. In a pulverizing jaw crusher, a fixed pulverizing plate, a pulverizing plate arranged for reciprocatory movement above said fixed plate, a shoe arranged above said reciprocating plate, the upper surface of which shoe is curved lengthwise, spring held means bearing on said shoe for yieldingly resisting the upward movements of said shoe and reciprocating plate, means for supporting said reciprocating plate and shoe and maintaining the latter in engagement with said roller, means for delivering material to be pulverized onto said fixed pulverizing plate and screens arranged to the sides of said fixed pulverizing plate.
10. In a pulverizing jaw crusher, a body member, a pulverizing plate fixed to said body member, a beam arranged for reciprocatory movement above said body member, means for imparting reciprocatory movement to said beam, a pulverizing plate carried by the free end of said beam and arranged above said fixed pulverizing plate, a shoe mounted on the free end of said beam, said shoe having a curved upper surface, means for counterbalancing the weight of the free end of said beam and maintaining same in operative position above the fixed pulverizing plate, a pair of arms pivoted at one end to said body member, a roller carried by the free ends of said arms, which roller engages the curved upper face of said shoe, adjustable means for yieldingly resisting the upward movement of the free ends of said arms and said roller and adjustable means for limiting the upward movement of the free ends of said arms and roller.
11. In a pulverizing jaw crusher, a body member, a pulverizing plate fixed to said body member, a beam arranged for reciprocatory movement above said body member, means for imparting reciprocatory movement to said beam, a pulverizing plate carried by the free end of said beam and arranged above said fixed pulverizing plate, a shoe mounted on the free end of said beam, said shoe having a curved upper surface, means for counterbalancing the weight of the free end of said beam and maintaining same in operative position above the fixed pulverizing plate, a pair of arms pivoted at one end to said body member, a roller carried by the free ends of said arms, which roller engages the curved upper face of said shoe, adjustable means for yieldingly resisting the upward movement of the free ends of said arms and said roller, adjustable means for limiting the upward movement of the free ends of said arms and roller, means for delivering material to be pulverized onto said fixed pulverizing plate and screens arranged at the sides of said fixed pulverizing plate.
12. In a pulverizing jaw crusher, a fixed pulverizing plate, a beam, means for simultaneously reciprocating and tilting said beam, a jaw carried by said beam the upper surface of which beam is concave longitudinally and disposed above said fixed plate, a shoe carried by said beam and a roller engaging the concave upper surface of said shoe and providing a fulcrum for the beam during its tilting movement.
13. In a pulverizing jaw crusher, a fixed pulverizing plate, a pulverizing plate arranged for reciprocatory movement above said fixed plate, a shoe positioned above said reciprocating plate, the upper surface of which shoe is concave longitudinally, a roller supported for vertical movement and bearing on the concave surface of said shoe, means for yieldingly resisting the upward movement of said roller and means for limiting the upward movement of said roller.
14. In a pulverizing jaw crusher, a fixed pulverizing plate, a pulverizing plate arranged for reciprocatory movement above said fixed plate, a shoe positioned above said reciprocating plate, the upper surface of which shoe is concave longitudinally, a roller supported for vertical movement and bearing on the concave surface of said shoe, means for yieldingly resisting the upward movement of said roller, means for limiting the upward movement of said roller and means for yieldingly raising said shoe and maintaining the same in contact with said roller.
15. In a pulverizing jaw crusher, a fixed pulverizing plate, a pulverizing plate arranged for reciprocatory movement above said fixed plate, a shoe carried by and positioned above said reciprocating plate, the upper surface of which shoe is concave longitudinally, spring held means bear-

ing on the concave surface of said shoe for yieldingly resisting the upward movements of said shoe and reciprocating plate and means for limiting the upward movement of said spring held 5 means.

16. In a pulverizing jaw crusher, a fixed pulverizing plate, a pulverizing plate arranged for reciprocating movement above said fixed plate, a shoe carried by and positioned above said reciprocating plate, the upper surface of which shoe

is concave longitudinally, spring held means bearing on the concave surface of said shoe for yieldingly resisting the upward movements of said shoe and reciprocating plate, means for limiting the upward movement of said spring held 5 means and yieldable means for maintaining said reciprocating plate in engagement with said spring held means.

CHARLES J. ZILLGITT. 10
